AXEL H. LONBOM AND GEORGE R. RODGERS, OF DANVILLE, ILLINOIS.

DOOR CLOSING AND CHECKING MECHANISM.

1,177,641.

Specification of Letters Patent.

Patented Apr. 4, 1916.

Application filed August 17, 1914, Serial No. 857,126. Renewed January 8, 1916. Serial No. 71,134.

To all whom it may concern:

Be it known that we, AXEL H. LONBOM and GEORGE R. RODGERS, citizens of the United States, and residents of the city of 5 Danville, county of Vermilion, and State of Illinois, have invented certain new and useful improvements in Door Closing and Checking Mechanism, of which the following is a specification.

10 Our invention relates to door closing and checking mechanism and has for its object the production of mechanism of this character which will be of durable and economical construction, efficient in operation, and 15 which will permit the door to be opened in either direction and will close the same with certainty but without violence.

Other objects will appear hereinafter.

With these objects in view our invention 20 consists in the combinations and arrangements of parts hereinafter described and claimed.

The invention will be best understood by reference to the accompanying drawings 25 forming a part of this specification, and in which—

Figure 1 is a central section through a device embodying my invention, the same being shown applied to a door, Fig. 2 is a 30 section taken on line $x-x$ of Fig. 1, Fig. 3 is a top plan view of the device detached, Fig. 4 is a view similar to Fig. 2 of a slightly modified form of the device, Fig. 35 5 is a top plan view of the construction shown in Fig. 4, and Fig. 6 is an enlarged section taken on line $y-y$ of Fig. 4.

The preferred form of construction as illustrated in the drawing is applied to a swinging door 1 which is mounted in a door 40 frame or casing 2. The swinging connection between the door 1 and frame 2 is of the usual type at the lower edge of the door, and hence is not shown, the connection between the upper edge of the door and said 45 frame comprising a spindle 3 fixed against rotation at its upper end in a plate 4 which is secured rigidly to the adjacent side of frame 2. The lower end of spindle 3 projects into the upper enlarged end portion 50 5' of a cylinder 5 which is secured in the door 1, said end of said spindle being loosely or rotatively engaged by a plate 6 secured by screws 7 in the cylinder portion 5'. The arrangement is such, as will be seen 55 that, in the operation of the door the latter

swings about the spindle 3 as a center. Formed at the lower end of spindle 3 is a segmental bevel gear 8. Arranged below the gear 8 and at either side thereof are segmental bevel gears 9 and 9' connected together by means of an integral hub 10, said gears 9 and 9' being mounted for free oscillation upon a transversely extending pin 11 mounted in the cylinder portion 5'. The arrangement is such that upon swinging of 65 the door in one direction from closed position the gear 9 will be brought in mesh with the stationary gear 8 so as to be rotated by the latter in a direction to cause arms 12 projecting from the hub 10 to be 70 rocked upwardly. Likewise, upon swinging of the door in the opposite direction from closed position, the gear 9' will be engaged with the gear 8 and be correspondingly oscillated by the latter in order to 75 effect corresponding upward rocking of the arms 12. Thus it will be seen that swinging of the door in either direction from closing position results in upward rocking being imparted to arms 12. 80

The outer ends of arms 12 are connected by means of a link 13 with a piston 14 which is mounted for reciprocation in cylinder 5, the arrangement being such that upon oscillation of arms 12 as just described, reciprocatory movement will be imparted to said piston. 85

The gears 8, 9 and 9' are so arranged that when the gears 9 and 9' are in neutral position that is out of engagement with the gear 8, the piston 14 is positioned at its lower terminal of movement in cylinder 5 and the door is in closed position. Interposed between the upper side of said piston and a plate 15 secured in the upper side of cylinder 5 is a helical compression spring 16 which exerts a pressure tending to normally hold said piston at its lower terminal of movement and hence the door in closed position, swinging of the door to open position, which results in upward movement of the piston, being resisted by the pressure of said spring. 90 95 100

In practice the interior of the member 5—5' is filled with oil or other suitable fluid which is adapted, upon reciprocation of the piston 14 to pass from one side thereof to the other. Said piston is provided with an opening 17 which is controlled by a ball valve 18, said valve being so arranged 105 110

as to permit of ready flow of the oil through said passage from the upper to the lower side of the piston upon upward movement of the latter but to prevent flow in the opposite direction upon return movement of the piston as will be readily understood. For the regulation of the flow of oil during the downward movement of the piston, a rod 19 is provided the lower end of which passes loosely through a passage 20 formed in said piston. The upper end of said rod is secured by means of a head 21 to the member 6 against longitudinal movement but in such a manner as to permit of rotative adjustment of said rod when desired, the periphery of said head being knurled for this purpose. The rod 19 is cut away at one side to form a slot 22 which is adapted, upon movement of piston 14, to register with the passage 20 and thus afford communication between the opposite sides of the piston to permit of the passage of the oil from the lower to the upper side thereof. The slot 22 is of graduated depth as shown being of greatest depth at its upper end so that in the downward movement of the piston, as the latter approaches its downward terminal of movement, the flow of oil from the lower to the upper side of the piston 30 will be gradually restricted. Leading from the lower end of the slot 22 is a very narrow passage 23 which registers with the upper end of a by-passage 24 leading from the lower or pressure side of piston 14. The upper end of passage 23 is so positioned that the same will register with the upper end of passage 24 when the door is about a foot from its closed position in which event the lower end of passage 20 will be closed through registration with the un-slotted lower end of rod 19 so that the only communication between the upper and lower sides of the piston will be through passage 24 and slot 23 which will obviously result in a maximum restriction in the flow of the oil from one side of the piston to the other during the last foot of movement of the door. Violent closing of the door is thus prevented. The flow from slot 23 through passage 24 is further regulated through rotative adjustment of rod 19 which is afforded by the head 21, it being clear that upon such adjustment the size of the upper end of passage 24 will be enlarged or diminished through the full or partial registration of the slot 23 therewith.

The form shown in Figs. 4, 5 and 6 is the same as that described except that instead of the lower end of slot 22 communicating with a restricted slot 23, the former is tapered down to a very small depth at its lower end or to the point 25 and from this point to the point 26 a straight slot of very small or limited depth is formed for registration with the upper end of the passage

24, as clearly shown in Figs. 4 and 6. Also in this form a screw 27 threaded in the portion 5' is provided for rotatively adjusting the rod 19, the inner end of said screw loosely engaging with the outer bifurcated end of an arm 28 projecting from the upper end of said rod as shown in Fig. 5. With this arrangement it will be seen that rotative adjustment of said rod is effected by adjustment of screw 27, said screw serving to positively lock said rod in its position of rotative adjustment.

With a construction as set forth it will be seen that little resistance is offered in the swinging of the door to open position, in which movement of the door the piston moves upwardly; but that in the closing movement of the door, the resistance will be increased by reason of the restriction of the flow of the oil from the lower to the upper side of the piston, in the downward movement of the latter, so as to prevent too rapid closing of the door, the maximum resistance being reached when the door is within substantially a foot of its closed position which serves to arrest the door as the same reaches its closing position.

While we have illustrated and described the preferred forms of construction for carrying our invention into effect, these are capable of variation and modification without departing from the spirit of the invention. We, therefore, do not wish to be limited to the precise details of construction set forth, but desire to avail ourselves of such variations and modifications as come within the scope of the appended claims.

Having described our invention what we claim as new and desire to secure by Letters Patent is:

1. A door closer and check comprising a stationary spindle about which the door is adapted to swing; a cylinder carried by the door; a piston mounted for reciprocation in said cylinder; a segmental gear on said spindle; an oscillatory shaft; an operative connection between said shaft and said piston whereby the latter is reciprocated through oscillation of said shaft; and an operative connection between said shaft and said segmental gear whereby said shaft will be oscillated upon swinging of the door, the last mentioned connection comprising a pair of segmental gears on said shaft at either side of said first mentioned gear and adapted for meshing with the latter during swinging of the door in either direction, substantially as described.

2. A door closer and check comprising a stationary spindle about which the door is adapted to swing; a cylinder carried by the door; a piston mounted for reciprocation in said cylinder; a segmental gear on said spindle; an oscillatory shaft; an arm on said shaft; a link connecting said arm with said

piston whereby the latter is reciprocated through oscillation of said shaft; and an operative connection between said shaft and said segmental gear whereby said shaft is oscillated upon swinging of the door, the last mentioned connection comprising a pair of segmental gears on said shaft at either side of said first mentioned gear and adapted for meshing with the latter during swinging of the door in either direction, substantially as described.

3. A door closing and checking mechanism comprising a cylinder containing fluid; a piston mounted in said cylinder and adapted to be reciprocated in said cylinder upon swinging of the door; a passage in said piston through which the fluid in said cylinder may pass from one side of said piston to the other; means comprising a stationary rod passing loosely through said passage having a slot in one side thereof for regulating the flow of fluid through said passage, said slot being of graduated depth whereby the flow of fluid through said passage will be restricted as said piston nears a position in said cylinder wherein the door is closed; and a by-passage in said piston of comparatively minute diameter communicating at one end with the pressure side of said piston and registering at its opposite side with the slotted side of said rod, substantially as described.

4. A door closing and checking mechanism comprising a cylinder containing fluid; a piston mounted in said cylinder and adapted to be reciprocated in said cylinder upon swinging of the door; a passage in said piston through which the fluid in said cylinder may pass from one side of said piston to the other; means for regulating the flow of fluid through said passage, said means comprising a rod fixed against longitudinal movement but adapted for rotary adjustment, said rod having a slot in one side thereof of graduated depth whereby the flow of fluid through said passage will be restricted as said piston nears a position in said cylinder wherein the door is closed; a by-passage in said piston of comparatively minute diameter communicating at one end with the pressure side of said piston and registering at its opposite end with the slotted side of said rod; and means for rotatively adjusting said rod to regulate the size of the end of said by-passage registering with said rod, substantially as described.

5. A door closing and checking mechanism comprising a cylinder containing fluid; a piston mounted in said cylinder and adapted to be reciprocated in said cylinder upon swinging of the door; a passage in said piston through which the fluid in said cylinder may pass from one side of the piston to the other; means for regulating the flow of fluid

through said passage, said means comprising a rod fixed against longitudinal movement but adapted for rotary adjustment, said rod having a slot in one side thereof through which the fluid may pass from one side of said piston to the other; a by-passage in said piston of comparatively minute diameter communicating at one end with the pressure side of said piston and registering at its opposite end with the slotted side of said rod; and a screw for rotatably adjusting said rod to regulate the size of the end of said by-passage registering with said rod, substantially as described.

6. A door closing and checking mechanism comprising a cylinder containing fluid; a piston mounted in said cylinder and adapted to be reciprocated in said cylinder upon swinging of the door; a passage in said piston through which the fluid in said cylinder may pass from one side of the piston to the other; means for regulating the flow of fluid through said passage, said means comprising a rod fixed against longitudinal movement but adapted for rotary adjustment, said rod having a slot in one side thereof through which the fluid may pass from one side of said piston to the other; a by-passage in said piston of comparatively minute diameter communicating at one end with the pressure side of said piston and registering at its opposite end with the slotted side of said rod: a laterally projecting arm on said rod; and a screw engaging with said arm for rotatably adjusting said rod to regulate the size of the end of said by-passage registering with said rod, substantially as described.

7. A door closing and checking mechanism comprising a cylinder containing fluid; a piston mounted in said cylinder and adapted to be reciprocated in said cylinder upon swinging of the door; a passage in said piston through which the fluid in said cylinder may pass from one side of the piston to the other; means for regulating the flow of fluid through said passage, said means comprising a rod fixed against longitudinal movement but adapted for rotary adjustment, said rod having a slot in one side thereof through which the fluid may pass from one side of said piston to the other; a by-passage in said piston of comparatively minute diameter communicating at one end with the pressure side of said piston and registering at its opposite end with the slotted side of said rod: a laterally projecting arm on said rod having a bifurcated outer end; and a screw threaded in said cylinder and having a circumferential groove at its inner end engaging in the bifurcation of said projecting arm for rotatably adjusting said rod to regulate the size of the end of said by-passage registering with said rod, substantially as described.

8. In a door check, the combination of a shaft, a piston operable by said shaft, a rod having main and auxiliary cut-out portions and mounted to project through said piston, and a by-pass in said piston communicating with said auxiliary cut-out, substantially as described.

In testimony whereof we have signed our

names to this specification in the presence of two subscribing witnesses.
